CLAIM

The ornamental design for a timer toy, as shown and described.

DESCRIPTION

FIG. 1 is a first perspective view of our timer toy.

FIG. 2 is a front view thereof.

FIG. 3 is a back view thereof.

FIG. 4 is a right side view thereof.

FIG. 5 is a left side view thereof.

FIG. 6 is a top view thereof.

FIG. 7 is a bottom view thereof; and,

FIG. 8 is a second perspective view thereof.

The broken lines illustrate portions of the timer toy that form no part of the claim.

1 Claim, 7 Drawing Sheets(56)
